(74) Attorney, Agent, or Firm — Robert C. Montgomery; Montgomery Patent and Design, LP.

(57) **CLAIM**

The ornamental design for a cribbage board game, as shown and described.

DESCRIPTION

FIG. 1 is a perspective top side view of the cribbage board game, showing my new design;

FIG. 2 is a left side view with the right side view, front side view and back side view being a mirror image thereof;

FIG. 3 is a top side view thereof; and,

FIG. 4 is a bottom side view thereof.
